ATTORNEY

UNITED STATES PATENT OFFICE.

ADOLPH OSWALD ZIENER, OF NEW YORK, N. Y., ASSIGNOR TO DISPLAY FOUNTAIN MANUFACTURING COMPANY, INC., A CORPORATION OF NEW YORK.

FOUNTAIN.

1,243,126.

Specification of Letters Patent. Patented Oct. 16, 1917.

Continuation in part of application Serial No. 3,830, filed February 15, 1915. This application filed December 9, 1916. Serial No. 135,955.

To all whom it may concern:

Be it known that I, ADOLPH OSWALD ZIENER, a subject of the Empire of Germany, and resident of the borough of Manhattan, city, county, and State of New York, have invented certain new and useful Improvements in Fountains, of which the following is a specification.

This invention relates to improvements in fountains, and particularly fountains of the type known as self contained fountains, that is, fountains in which the power plant is directly carried by and is in proximity to the pump and spray apparatus. An object of the present invention is to provide such a fountain device, which is portable and detachable, enabling the same to be placed in any suitable basin, in which a sufficient amount of water may be contained. A further object is to provide such a fountain which is compact, simple in construction and in which the working parts are thoroughly protected from moisture and in which the necessity for packing is dispensed with. With these and other objects in view, embodiments of my invention are shown in the accompanying drawings and these embodiments will be hereinafter more fully described, with reference thereto and the invention will be finally pointed out in the claims.

In the accompanying drawings:

Figure 1 is a vertical sectional view of one embodiment of my invention;

Fig. 2 is a similar view of a slightly modified form;

Fig. 3 is a further modified form in which an electric motor is employed as the power producing element;

Fig. 4 shows another modification in which an electric motor is employed; and

Fig. 5 is a sectional view in which illuminating means are embodied with other features of the invention.

Similar reference characters indicate corresponding parts throughout the several figures of the drawings.

Referring to the drawings and more particularly to Fig. 1 thereof, an embodiment of my invention comprises a pump housing 10, having a laterally extending flange 11 at its upper edge. The upper portion of the housing is of wider interior diameter than the lower portion thereof, so that a shoulder

13 is formed, upon which a partition plate 55 14 is secured, by means of screws 15, the said plate being provided centrally with an opening 16. A plurality of water inlet openings 34 are provided in the upper portion of the wall of the housing and a motor 60 17 is mounted upon the flange 11 and secured thereto by means of screws 18, which motor is shown in this form of my invention, as a clock work mechanism or spring motor. A driving shaft 19 extends downwardly therefrom and is suspended through the opening 16 of the partition plate 14, being spaced from the wall of said opening and provided upon its lower end with a fan or turban 20, which is slightly spaced at all 70 sides from the walls of the housing and the partition plate.

An annular tubular rim 21 provided with a plurality of inwardly directed jet nozzles 22 is supported in spaced relation from the 75 housing, by means of radial arms 23, secured to lugs 24, upon the outer surface of the housing, by means of screws 25 and is connected to the housing, by means of a tube 26, which is provided with a valve 33. 80

A cover 27, which in the embodiment herein is shown bell shaped and which may be of any suitable and preferably ornamental design is placed over the motor and housing and is secured to the rim 12 of the 85 motor by screws 32, a flange 28 being provided upon the interior of the said cover through which the screws pass. The surface of the cover may be provided with a plurality of furrows 31, which form descending 90 paths for the water or the same may take the shape of a succession of annular undulations, forming a cascade over which the water may descend to the basin. It will be obvious that any other suitable and ornamental shape may be given to the cover, which will permit the falling water to descend to the basin. This cover acts as a water shed and thoroughly protects the working parts from the falling water, which is discharged upwardly and inwardly by the jet nozzles. The lower edge of the cover is provided with rubber feet 29 which rest on the bottom of the basin 30 and permit the water to pass beneath the cover. This 95

100 fountain may be placed in any suitable basin of sufficient depth to contain water to the level of the openings 34 and of sufficient width to 105

accommodate the annular ring 21. With applicant's device, an extremely shallow basin may be employed, which is quite pleasing and artistic in appearance.

5 In operation, the basin is first filled with water, so that the openings 34 are covered, permitting the water to flow therethrough and through the opening 16 of the partition plate into the pump housing. The 10 clock work mechanism is wound by means of the key 17^a and water is forced through the tube 21 from the housing by operation of the fan or turban 20 and is sprayed from the ring 21 upwardly and inwardly by the 15 jet nozzles thereof, falling upon the cover 27 and returning to the basin, the same water being used continuously during this spraying and return flow, the same, of course, being replenished, as evaporation occurs. The motor, it will be seen, at no time 20 is accessible to the water, so that there is no danger of the operation of the same becoming impaired thereby and by reason of the suspension of the pump through the enlarged opening 16, the necessity for packing 25 is dispensed with.

In the form of construction shown in Fig. 2, the annular tubular ring 21 is removed and a central spraying member 40, 30 which may be of any suitable form, and illustrated as taking the form of dolphins 43 and a central spray nozzle 44, is provided at the upper portion of the cover 41 and is connected to the pump housing, by means 35 of a tube 42, having a valve 45 and which passes through the rim 12 of the motor. The upper portion of the cover 41 is recessed as at 41^a and is adapted to receive a small amount of water which overflows at 40 the overhanging portion 41^b. The operation is similar to that described, with reference to Fig. 1, with the exception that the water is forced through the tube 42, and delivered in several fountain like jets from the 45 nozzle 40. The force of these jets may be regulated or the flow entirely cut off by the valve 45. The basin in this form is provided with a recessed portion 46, claw feet 47 or other suitable supports being provided 50 therefor.

In Fig. 3, I have shown another modified form of construction, in which an electric motor 50 is provided as a power plant, the current being supplied thereto by wires 51, 55 which extend through a waterproof tube 52, said tube being of such length as to extend beyond the periphery of the annular rim 21' having the jets 22' and then upwardly at its end, as at 53, so as to be entirely without 60 the reach of the water, thereby protecting the wire from moisture. The pump in this form is larger and is provided with a flange 54 to which the motor is secured by screws 55 and a rim 56 on the flange for supporting 65 the cover 57 which is provided with open-

ings 58 to permit entrance of water to the pump. A basin similar to that shown in Fig. 2 is provided.

In the form of construction shown in Fig. 4, a similar electric motor 60, which is supplied with current through wires 61, extending through the waterproof tube 62 is provided in conjunction with a form of construction, such as is shown in Fig. 2, in which a central spraying nozzle 63 is provided instead of the annular tubular rim. The same is shown as disposed in a basin similar to that shown in Fig. 1.

In Fig. 5, I have shown a still further modification, in which I provide both an annular ring 70, having a plurality of jet nozzles 71, and a central jet nozzle 72, having a valve 73 therein, and respectively connected to the pump housing, by means of tubes 74 and 75, the tube 74 being provided 80 with a controlling valve 76. The cover 77 is constructed of a material, which is not impervious to light, such, for instance, as translucent glass, rock crystal or the like, and beneath the same and preferably upon 85 the upper surface of the electric motor 78, there are mounted one or more electric lamps 79, which may be of different colors and which are supplied with current to the wires 80, which together with the wires 81 for 90 the motor extend through the waterproof tube 82. The illuminated water shed, together with the central and annular water sprays, combine to produce a very pleasing 95 effect. By reason of the portability of the fountain, which permits of its being placed 100 in any suitable basin, the invention lends itself to many ornamental uses. Thus, for instance, the same fountain may be placed on a table in a basin, or bowl, of sufficient 105 depth, or the same may be placed in a garden or the like, in any suitable water container, which may be accessible, and where permanent basins are installed in parks, the 110 fountain may be placed therein without in 115 any way altering the same.

I have illustrated and described, preferred and satisfactory forms of my invention, but it is obvious that changes may be made therein, within the spirit and scope thereof, 115 as defined in the appended claims.

I claim:

1. A self contained fountain comprising a basin, a pump disposed in said basin, a pump housing surrounding said pump and provided with openings communicating with the interior of said basin below the normal water level thereof, a motor disposed over said pump and pump housing and provided with a driving shaft in operative connection with the shaft of said pump, a spraying device connected with the delivery of said pump, and a cover disposed in said basin, open at its bottom, inclosing said motor, pump and pump housing and also 120 125 130

serving as a water shed for spray water of said spraying device, said apparatus being adapted to operate upon a quantity of water contained in said basin, the same water being passed repeatedly by means of the pump through said spraying device and regathered in said basin.

2. A self contained fountain comprising a basin, a pump disposed in said basin, a pump housing surrounding said pump and provided with openings communicating with the interior of said basin below the normal water level thereof, a motor disposed over said pump and pump housing and provided with a driving shaft in operative connection with the shaft of said underneath pump, a jet pipe disposed with-

in and extending around said basin, connected with said pump and provided with a series of upwardly and inwardly inclined 20 jet nozzles, and a dome-like cover disposed in said basin, between said pump and jet pipe, open at its bottom, inclosing said motor and serving as a water shed for directing the spray water of said nozzles back 25 into said basin.

In testimony that I claim the foregoing as my invention, I have signed my name in presence of two subscribing witnesses.

ADOLPH OSWALD ZIENER.
